US00D444352S

(12) **United States Design Patent** (10) Patent No.: **US D444,352 S**
Tramontina et al. (45) Date of Patent: ** *Jul. 3, 2001

(54) **NAPKIN DISPENSER**

1,989,381 1/1935 Samson 312/62
 2,143,614 1/1939 Winter et al. 206/57

(75) Inventors: **Paul Francis Tramontina**, Alpharetta;
Jan Byron Charles Spencer, Roswell,
 both of GA (US)

(List continued on next page.)

(73) Assignee: **Kimberly-Clark Worldwide, Inc.**,
 Neenah, WI (US)
